(57) **CLAIM**

The ornamental design for [umbrella poles and endcap for
patio or beach] *endcap and poles*, as shown and described.

DESCRIPTION

The characteristic features of the design reside in a curved
umbrella pole with ornamental endcap and a middle pole
section [that is half-filled with packed sand and half-filled
with concrete for stabilization].

The FIGURE is a side perspective view of the [entire]
umbrella [and base thereof,] with *endcap and poles* shown in
an exploded view for clarity of illustration.

The broken [line] lines showing [of the] *the base, crank shaft,
tilt mechanism, and [parasol] is] *umbrella, the hollow interior
of the lower portion of the pole and the hole in the lower
portion of the pole that is oriented generally perpendicular to
the longitudinal axis of the pole* are for illustrative purposes
only and [forms] form no part of the claimed design.*
